UNITED STATES PATENT OFFICE.

ANDREW ALLAN, OF LEITH, SCOTLAND.

FLYING-MACHINE.

1,264,743.

Specification of Letters Patent. Patented Apr. 30, 1918.

Application filed August 14, 1917. Serial No. 186,250.

To all whom it may concern:

Be it known that I, ANDREW ALLAN, a subject of the King of Great Britain and Ireland, residing at 42 Cambridge Gardens, 5 Leith, Edinburgh county, Scotland, have invented certain new and useful Improvements in Flying-Machines, of which the following is a specification.

This invention relates to flying machines 10 and refers to constructional improvements in aeroplanes, hydroplanes and the like by which the lifting power and general efficiency of the machines are increased.

The invention refers more particularly 15 to machines of the type in question provided with tractors or screws placed at or near the front.

According to the general principle of 20 my invention the screw or tractor is placed in an inclined position under the plane or upper plane, and above a curved structure, open in front and closed behind, which structure I call the "scoop," the intention being that the air acted upon by the tractor 25 shall be thrown against the plane above, thus imparting a lifting impulse to the machine. A further lifting impulse, and also a propelling effect, are imparted by the partial exhaustion of the air inside the scoop, 30 and the consequent pressure of the atmospheric air on the bottom and end of the scoop.

In order that my said invention may be 35 clearly understood I will now proceed to describe the same with reference to the accompanying drawings which show, diagrammatically, one form of aeroplane constructed according to my said invention.

Figure 1 is a plan of the upper planes of 40 the machine, including an elevating rudder or tail plane.

Fig. 2 is a side elevation showing one position of the engine and car.

Fig. 3 is an end elevation.

45 The same letters of reference are employed to denote the same parts in all the views.

Referring to Fig. 1, the side planes or wings *a*, *a*, are of any ordinary construction, and may be cambered in the usual way and provided with ailerons *a*¹, as shown, at Fig. 2 for the purpose of "banking" and steering the machine laterally.

50 The central plane *b* may be curved in cross section, or plane, and it may be rela-

tively longer, shorter, narrower or broader than shown in the drawing.

A vertical rudder *k*, Fig. 2, is provided under the rudder *c* for horizontal steering purposes.

In Figs. 2 and 3, the tractor *e* is actuated by an engine *f* carried in any suitable manner by the framework *g*.

As will be seen, when the tractor revolves the air is thrown up against the underside 65 of the plane *b*, and at the same time the air is partially exhausted in the scoop *h*. In this way the tractor while pulling the machine forward, exerts a lifting impulse by the pressure of the air on the plane *b*, and 70 indirectly by the exhaustion of the air in the scoop *h*, and the pressure of the air below.

There is also a propelling effect exerted 75 on the end *j* of the scoop by the pressure of the air behind.

The rudders *c* and *k* may be controlled by levers and wires or other appliances from the car *l* which is attached to the framework indicated by the dot and dash lines in Fig. 1 and the lines *d* in Figs. 1 and 2. 80

A landing chassis *m*, Figs. 2 and 3, with wheels or floats is provided attached below the scoop.

In a modification of the construction, the engine may be placed below or behind the 85 scoop, and may drive the screw shaft by means of a chain and (or) beveled gear.

A car for the accommodation of passengers and (or) the pilot and (or) an observer may be arranged behind the scoop. 90

An auxiliary elevating rudder may be arranged in front of the scoop or the front end of the longitudinal plane may be adapted to this purpose.

In the case of large machines two or more 95 tractors and associated parts may be provided.

It will be understood that the invention is not limited to the particular way of carrying the same into effect hereinbefore described, but that the construction may be varied within the scope of the appended claims, without departing from the principle of the said invention.

What I claim and desire to secure by Letters Patent of the United States of America is:

1. In a flying machine the combination 105 of a plane, a scoop like structure located below the plane and having its open end 110

- directed forwardly and its closed end rearwardly with respect to the flying machine, and an inclined tractor mounted between the plane and the scoop, for the purposes set forth.
2. In a flying machine the combination of a plane, a curved scoop like structure located below the plane and having its open end directed forwardly and its closed end rearwardly with respect to the flying machine, and an inclined tractor mounted between the plane and the scoop substantially as and for the purposes set forth.
3. In a flying machine the combination of a plane, a curved scoop like structure located below the plane and having its open end directed forwardly and its closed end rearwardly with respect to the flying machine, and an inclined tractor mounted between the plane and scoop, the said tractor
- rotating in a plane inclined forwardly and upwardly with respect to the vertical axis of the machine, substantially as described.
4. In a flying machine, the combination of a main plane, side planes, a curved scoop like structure located below the main plane, and having its open end directed forwardly and upwardly with respect to the vertical axis of the machine, and an inclined tractor mounted between the main plane and the scoop, the said tractor rotating in a plane inclined forwardly and upwardly with respect to the vertical axis of the machine, substantially as described.

In testimony whereof, I affix my signature this 2nd day of August 1917.

ANDREW ALLAN.
